[57] **CLAIM**

The ornamental design for toy with pivotal sections for forming multiple faces, as shown and described.

DESCRIPTION

FIG. 1 is a front elevation of a toy with pivotal sections for forming multiple faces showing my new design in one of the possible arrangements;

FIG. 2 is a side elevation taken from the left of FIG. 1; FIG. 3 is a side elevation taken from the right of FIG. 1;

FIG. 4 is a side elevation taken from the rear of FIG. 1; FIG. 5 is a top plan view thereof; and FIG. 6 is a bottom plan view thereof.

FIG. 1

FIG. 2

FIG. 3

FIG. 4

FIG.5
